UNITED STATES PATENT OFFICE.

GEORGE A. GRIFFIN, OF OAKLAND, CALIFORNIA.

ILLUMINATED SIGN.

Application filed December 29, 1924. Serial No. 758,728.

To all whom it may concern:

Be it known that I, GEORGE A. GRIFFIN, a citizen of the United States, and resident of Oakland, in the county of Alameda and 5 State of California, have invented a certain new and useful Improvement in Illuminated Signs, of which the following is a specification.

This invention relates to that class of apparatus known as advertising signs when light is used to illuminate the parts for advertising and display purposes.

The invention more especially relates to that type of apparatus known as electric signs usually having a series of letters or figures mounted by a retainer and in which is placed a series of electric lights to illuminate the different letters or figures and make them visible where it is necessary to 20 use artificial light.

It is one of the objects of the present invention to improve the construction of an electric sign so as to make it superior in point of simplicity, inexpensive in operation 25 and having a general high efficiency.

It is another object of the invention to provide an electric sign with improved means to eliminate the excessive number of electric lights used in the present type of 30 electric signs.

It is a further object of the invention to provide an electric sign with improved adjustable means to reflect light against the part to be illuminated and thereby reduce 35 the cost of operating and maintaining the sign.

The invention possesses other objects and features of advantage some of which, with the foregoing, will be made manifest in the 40 following description of the preferred form of the invention which is illustrated in the drawings accompanying and forming part of the specification.

It is to be understood that it is not intended 45 to limit the invention to the embodiment shown by said drawings and descriptions, as variations may be adopted within the scope of the invention as set forth in the claims.

50 In the drawing:

Figure 1 is a central longitudinal sectional view of one type of sign involving the invention.

55 Figure 2 is an outside view looking directly in front of the sign and using the word Drugs for illustration.

Figure 3 is an end section showing one method of pivotally mounting a reflector.

Figure 4 is a mirror or reflector mounted 60 on a frame.

Figure 5 is a half section showing a spot light and some of the reflectors.

Figure 6 is a perspective view with part of the top broken away showing the reflectors behind the letters.

Figure 7 is a vertical end sectional view of a modified form of reflector mounting, illustrating means for angularly adjusting the reflectors with respect to the source of illumination.

As said in the beginning the principal improvement consists in providing an electric sign with simple and effective means for eliminating some of the excessive number of lights used in the present type of sign and thereby reduce the cost of operating and maintaining the sign. These and other objects already mentioned are accomplished by providing an electric sign with a series of 70 adjustable reflectors of any shape or size placed at any angle or in any position desired, and to throw light against these reflectors and thereby reflect that light to the part or parts to be illuminated.

In Figure 1 is shown a series of reflectors 3 in a housing 4 in which there is a spot light 5 thrown against these series of reflectors 3. The reflectors 3 are located behind the letters 6 and placed at any angle necessary to throw a direct reflection from the 80 spot light against the letters necessary to illuminate; the word Drugs in this case being used for illustration.

In the modified form illustrated in Figure 7, a rear closure panel 7 is provided 95 with inwardly directed longitudinal flanges 8 and 9, having suitable openings adapted for the reception of the thumb screws 10, the shank ends of which are adapted for engagement with the interior surface of the top and bottom walls of the casing, when the said screws are adjusted to hold the rear panel 7 in adjusted position with respect to the front wall, having the character indicating openings 6.

100 In this instance, a series of reflectors 3 is arranged in spaced relation forwardly of the rear closure panel 7. A plurality of posts 11 are suitably secured to the rear closure panel 7 and connected thereto, are 110 the sleeves 12 centrally apertured for the reception of the vertical portion 13 of the

hanger rods 14, secured to the lower rear surface of each of the reflectors 3.

The entire series of reflectors is mounted on the rear panel 7 and may be adjusted in 5 horizontal plane with respect to the character designations 6 and the illuminating source 5.

Resultant of the novel pivotal connection of the reflectors 3 upon the posts 11, the 10 former are capable of adjustment in angular plane to the front wall having the character designations 6, and likewise in angular plane with relation to the illuminating source 5.

15 The novel mounting of the reflectors 3 in the manner stated provides for the collective adjustment of reflector series and the universal adjustment of each individual reflector.

20 Likewise, each reflector 3 is capable of adjustment in direct vertical plane by loosening the screws, not illustrated, in the sleeves 12. These screws have end engagement with the vertical portions 13 of the 25 hanger rods 14, so that the reflectors may be individually raised or lowered.

It will thus be seen that by throwing a direct reflection against each individual letter or part that is to be illuminated, the 30 intensity of the light is confined to these particular spots, and therefore will require a less number of lights with the result of less operating and maintaining costs.

What is claimed is:

35 1. An illuminated sign comprising a receptacle having a front wall provided with character defining openings, a closure panel adjustably connected to said receptacle, an illuminating element in said receptacle, a 40 series of reflectors arranged on said closure panel and means for adjusting said reflect-

tors with respect to the character openings and illuminating element.

2. An illuminative sign comprising a receptacle provided with a wall having a series of letters or figures thereon, a closure panel adjustably mounted in said receptacle, an electric light in said receptacle, a series of reflectors arranged on said panel and being capable of universal adjustment with 45 respect to said electric light and letters or figures.

3. In an illuminative sign, the combination with a housing receptacle having a series of letters or figures, of an illuminating element in said receptacle, a panel for closing said receptacle, a series of reflectors mounted on said panel and said reflectors and said panel being adjustable with respect to said letters or figures and said illuminating element.

4. An illuminative sign, the combination with a receptacle having character defining openings in one wall thereof, a panel for closing said receptacle, a lighting element arranged in said receptacle, a series of reflectors mounted on said closure panel, said panel adapted for adjustment within said receptacle and said reflectors being capable of vertical and angular adjustment with respect to said lighting element.

5. An electric sign, the combination with a receptacle having character defining openings in the front wall thereof and a closure panel, a lighting element arranged in said receptacle, a plurality of posts disposed on said closure panel, a series of reflectors mounted on said posts and means for adjusting the position of said reflectors on said posts with respect to the character defining openings and lighting element.

GEORGE A. GRIFFIN.
